MICROWAVE COAXIAL TERMINATION

Vincent J. McHenry, Farmington, Mich., assignor to
Omni Spectra, Incorporated, Detroit, Mich., a corpora-
tion of Michigan

Filed Sept. 12, 1962, Ser. No. 223,152

14 Claims. (Cl. 333—22)

This invention relates to apparatus for absorbing the incident power of electromagnetic waves within the microwave spectrum and also relates to the method of making such apparatus.

In many instances it is necessary to have a device terminating an electrical circuit capable of absorbing incident power over the entire microwave spectrum, i. e., 15 1000 megacycles per second to 12,000 megacycles per second, with substantially no reflection of the incident wave. One application for such a terminating device is where it is desired to determine or measure various characteristics of microwave equipment, i.e., as for a coupling, in which it is necessary for test purposes that there be substantially no reflected energy from a particular propagation path. In some microwave apparatus, ports are provided across various stages of the circuits to allow measurements to be made at these points. Another example of use for the microwave termination would be to terminate these ports. It is an object of this invention to provide a novel microwave termination for substantially absorbing the incident power of electromagnetic waves within the microwave spectrum.

One type of microwave termination is of a coaxial construction having a center conductor and an outer shield with a lossy or microwave absorbing material disposed between the center conductor and the outer shield. Since the amount of reflected energy from the microwave termination must be maintained at a minimum, good impedance-matching must be obtained between the termination and the line with which it is associated. To facilitate impedance-matching, it has been conventional practice to form the lossy material in the shape of a long taper, tapering into substantially a knife-edge at the input end, with the length of the taper being approximately equal to two wave lengths of the lowest frequency within the microwave spectrum to be absorbed. While such a construction is effective, it does necessitate the use of a termination which is rather long. It is an object of this invention to provide a microwave coaxial termination of a relatively small size for substantially, completely absorbing, with minimum reflection, incident power of electromagnetic waves within the microwave spectrum.

In order to more completely absorb microwaves of a particular frequency, it has been the practice to construct terminations of the long taper type, previously mentioned, in which the tapered lossy material or load is movable axially relative to the shield and center conductor. By properly adjusting the location of the load along the line, the point of maximum absorption can be found for that given frequency. It is an object of this invention to provide a novel termination for absorbing the incident power of electromagnetic waves within the microwave spectrum in which means are provided for accurately adjusting the termination for maximum absorption of a desired frequency.

It is a further object of this invention to provide a novel method for making the microwave termination of the above described type.

Other objects, features, and advantages of the present invention will become apparent from the subsequent description and the appended claims, taken in conjunction with the accompanying drawings in which:

2

FIGURE 1 is a side elevational, sectional view, with some parts shown broken away, of a microwave termination exemplifying the features of this invention;

5 FIGURE 2 is a side elevational, sectional view, with some parts shown broken away, of a termination of modified construction, exemplifying the features of this invention; and

10 FIGURE 3 is a fragmentary, side elevational, sectional view depicting a modification of the termination shown in FIGURE 1.

Looking now to FIGURE 1, a coaxial termination, exemplifying the features of this invention, is generally indicated by the numeral 10 and has a coaxial conductor 12 having an input end portion 14 and a coiled, termination end portion 16. The coaxial conductor 12 can be of a conventional construction having a center conductor 11 surrounded by an outer electrical conductor or shield 13 with the conductors 11 and 13 separated from each other by an electrical insulator 15. The termination portion 16 is coiled or wound in the form of a helix tapering radially inwardly while extending axially from its input end (connected to input end portion 14) to its opposite end. For the sake of convenience, the coiled portion 16 can be thought of as defining radially inner and outer surfaces. Thus the outside diameter along the radially outer surface of the termination portion 16 varies from a maximum at its input end to a minimum at its opposite end. Normally, of course, the radially inner surface of the coiled termination portion 16 would 20 be of a similarly tapered configuration. However, for a purpose to be presently seen, the radially inner surface of the termination portion 16 is cut substantially to a uniform diameter D. Thus, with the termination portion 16, the outer shield 13 is provided with an opening which 25 faces radially inwardly, with the opening being a minimum proximate the input end of the termination portion 16 and progressively increasing to a maximum at the opposite end. In the embodiment of FIGURE 1, the terminus of the coaxial coil 12 at the opposite end of the 30 termination portion 16 has been reduced to one-half its original cross section; note that, in reducing the cross section of the line 12, both the shield 13 and center conductor 11 are partially removed to provide more effective power dissipation. For practical reasons, the cross section is not reduced greater than one-half, since, with 35 less than one-half of the coaxial line 12 remaining, the mechanical connection maintaining the shield 13, insulator 15, and center conductor 11 together would be 40 broken.

45 In a preferred form, the total straightened length of the coiled termination portion 16 is approximately equal to twice the wave length of the lowest frequency of the microwave spectrum to be absorbed, i.e., for a termination to absorb the entire microwave spectrum the straightened length would be approximately equal to twice the 50 wave length of the 1000 megacycle per second wave.

The coaxial line 12 is located in a tubular housing 18 constructed of metal or plastic and having a generally circular cross section; in the embodiment of FIGURE 1 55 the housing 18 is made of a material which is a good conductor, i.e., high conductivity, of electricity. The housing 18 is of a substantially uniform diameter in the region of the termination portion 16 tapering at one end to a reduced diameter neck portion 19 which is of a diameter to matingly accommodate the terminus of the coaxial line 12 at the input portion 14. An epoxy resin, indicated by the numeral 20, can be applied between the housing 18 and the outside diameter of the terminating portion 16 to thereby secure the coaxial line 12 within 60 the housing 18. The opposite end of the housing 18 can be sealed by a cap 22. The terminus of line 12 at the 65 70

intermediate portion 16 is soldered or otherwise electrically connected to the cap 22.

Secured by a retainer ring 23 to the necked portion 19 of the housing 18 is a threaded female connector 24. The terminus of the input portion 14 of the coaxial line 12 has the center conductor 11 extending axially outwardly beyond the shield 13 and insulation 15 and is matably engageable with a suitable female connector (not shown) of a type well known in the art.

A core of lossy material 26 is located in the inside diameter of the terminating portion 16 and can be made of pressed carbon, a ferro magnetic loss material, or some other type of lossy material well known in the art.

By breaking or partially removing the outer shield 13 on the inside diameter of the coiled termination portion 16 in a manner whereby the microwave transmitted therethrough is gradually, progressively, increasingly exposed to the lossy material of the core 26, excellent impedance matching characteristics are obtained such that the reflected wave from the terminating portion 16 is a minimum.

FIGURE 2 depicts a modification of the embodiment of FIGURE 1 in which components having similar functions are given the same numbers with the addition of a letter subscript. In FIGURE 2 the microwave coaxial termination 10a has a coaxial line 12a having an input end portion 14a and a termination portion 16a which is helically wound to form a coil tapering radially inwardly which extends axially in a direction toward the input end portion 14a. Thus the inside diameter of the termination portion 16a varies from a minimum at the input end to a maximum at the opposite end. The outside diameter is cut to a diameter D_a such that the shield 13a is provided with an opening which faces radially outwardly, with the opening proximate the input end being a minimum and progressively increasing to a maximum at the opposite end. At the opposite end, the shield 13a and center conductor 11a have been approximately cut in half.

The terminating portion 16a can be provided with a center core of epoxy material 20a and is provided with a cylinder of lossy material 26a which extends peripherally about the outside diameter of the termination portion 16a. The coaxial line 12a can be mounted in a housing 18a which is similar to housing 18. Again, in the construction shown in FIGURE 2, the microwave energy traveling along the coaxial line 12a is gradually, increasingly exposed to the lossy material 26a, thereby providing a good impedance match resulting in substantially no reflection of the input wave.

Even with the most precisely constructed microwave terminations, total absorption is not obtained and some reflection of the incident wave occurs. As previously mentioned, one of the factors which can lead to variations in the degree of absorption for different frequencies is the position of the core of absorption material relative to the shield and to the center conductor. In order to allow the termination to be set for maximum absorption for a particular frequency, a sliding termination can be utilized whereby the lossy or absorbing material is moved relative to the coaxial line. In FIGURE 3 an adaption of the microwave termination construction of FIGURE 1 to a sliding termination is shown in which similar components having similar functions are given similar numbers with a letter subscript added. In FIGURE 3 a sliding termination, only partially shown, is generally indicated by the numeral 10b and has a coaxial line 12b, of a construction similar to that of coaxial line 12 of FIGURE 1, which is secured within an outer case or housing 18b. A core 26b of lossy material is slidably disposed within the inside diameter of the termination portion 16b and has a rod 28 secured at one end thereto. The opposite end of rod 28 is slidably supported in a bushing 30 supported in a coaxial extension portion 32 of the housing 18b. A knob 34 is secured to the rod 70

28 and is accessible through an elongated window or slot 36 located in the extension portion 32. Thus the knob 34 can be manipulated by hand to cause the lossy core material 26b to be moved axially relative to the termination portion of the coaxial line 12b to thereby allow the termination 10b to be set to provide for maximum absorption at a particular frequency. For the sake of convenience, calibration marks can be provided along the side of the slot 36 and a marker indicated on the knob 34 whereby the termination 10b can be calibrated for maximum absorption over a given frequency range. With the sliding termination 10b, greater changes can be effected with less axial movement of the core 26b than with sliding terminations of conventional construction. Thus a savings in size is realized. A similar adaption to a sliding termination could be provided for the termination 10a of FIGURE 2.

To make the termination 10 of FIGURE 1, in a preferred embodiment, a coaxial line having a length greater than two wave lengths of the lowest frequency in the microwave spectrum to be absorbed is obtained. Next, a portion of the coil, substantially equal to the two-wave length dimension, is wound into a helically, uniformly tapered coil to form the termination portion 16, with the large diameter end being proximate the remaining input portion 14 of the coaxial line. In general, the diameter to which the coaxial line is wound is not critical, hence allowing considerable variation in the final physical dimension of the termination.

Next, the internal diameter of the termination portion of the coil is cut to a uniform diameter D , preferably whereby the shield 13 at the first coil is just slightly broken while the cross section of the last coil is substantially reduced to one-half of its original cross section. In order to provide this relationship, the coil is tapered such that the inside diameter of the first coil at the large end is just slightly less than the uniform diameter D and the mean diameter of the last coil at the small end is substantially equal to the diameter D .

Next, a generally cylindrical slug 26 of lossy material is press-fitted into the inside diameter of the termination portion. The slug and coaxial line, as assembled, can then be assembled into a case or housing 18 having appropriate fittings.

The manufacture of the termination 10a of FIGURE 2 can be accomplished in a similar manner except that, in the embodiment of FIGURE 2, a portion of a coaxial line is wound into a tapered coil 16a having a gradually increasing diameter from its input end portion 14a. Next, the outside diameter is machined to a uniform diameter D_a whereby the amount of material removed from the outside diameter is a minimum proximate the input end and gradually increases, with the last coil being substantially cut in half. Next, a hollow cylinder of lossy material is press-fitted over the outside diameter D_a of the termination portion 16a. The coaxial line 12a assembly can then be assembled into an appropriate housing 18a.

While in none of the above constructions is the mean diameter of the coiled termination portion 16, 16a critical, a diameter should be selected which facilitates a gradual taper with a gradual change in the amount of exposure of the termination portion 16, 16a, to the absorbing member 26, 26a.

It can be appreciated that, in comparison to a termination either fixed or sliding of the tapered absorbing material type, terminations constructed in accordance with FIGURES 1, 2 and 3 are smaller, more compact, and lend themselves to a direct method of construction.

While it will be apparent that the preferred embodiments of the invention disclosed are well calculated to fulfill the objects above stated, it will be appreciated that the invention is susceptible to modification, variation and change without departing from the proper scope or fair meaning of the subjoined claims.

What is claimed is:

1. Apparatus for absorbing incident power of electromagnetic waves within the microwave spectrum comprising a coaxial line having a center conductor surrounded by an outer tubular shield, a termination portion of said coaxial line, said outer shield of said coaxial line of said termination portion being partially removed to define an opening progressively increasing from a minimum proximate an input end of said termination portion to a maximum at an opposite end, and a member of microwave absorbing material disposed proximate to and in confrontation with said opening.

2. Apparatus for absorbing incident power of electromagnetic waves within the microwave spectrum comprising a coaxial line having a center conductor surrounded by an outer tubular shield, a termination portion of said coaxial line, said coaxial line of said termination portion decreasing in cross sectional area gradually from one end of said termination portion to an opposite end with said outer shield of said coaxial line of said termination portion having an opening progressively increasing from a minimum proximate said one end of said termination portion to a maximum at said opposite end, an input portion of said coaxial line at said one end of said termination portion, and a member of microwave absorbing material disposed to and in confrontation with said opening.

3. Apparatus for absorbing incident power of electromagnetic waves within the microwave spectrum comprising a coaxial line having a center conductor surrounded by an outer tubular shield, a termination portion of said coaxial line, said coaxial line of said termination portion decreasing in cross sectional area gradually from one end of said termination portion to an opposite end with said outer shield of said coaxial line of said termination portion having an opening progressively increasing from a minimum proximate said one end of said termination portion to a maximum at said opposite end, an input portion of said coaxial line at said one end of said termination portion, a member of microwave absorbing material disposed to and in confrontation with said opening, and means operatively associated with said member and said termination portion of said coaxial line for moving said member relative to said termination portion.

4. Apparatus for absorbing incident power of electromagnetic waves within the microwave spectrum comprising a coaxial line having a center conductor surrounded by an outer tubular shield, a termination portion of said coaxial line defining a coil having inner and outer surfaces, one of said surfaces of said termination portion of said coaxial line having the material of said coaxial line partially removed with the amount of material removed from said one of said surfaces on adjacent coils gradually increasing from a minimum at one end to a maximum at the opposite end, an input portion of said coaxial line at said one end of said termination portion, and a member of microwave absorbing material disposed in peripheral proximity to said one of said surfaces of said termination portion.

5. Apparatus for absorbing incident power of electromagnetic waves within the microwave spectrum comprising a coaxial line having a center conductor surrounded by an outer tubular shield, a termination portion of said coaxial line defining an axially extending, radially tapering coil having similarly tapering radially inner and outer surfaces, one of said surfaces of said termination portion of said coaxial line having the material of said coaxial line partially removed to a substantially uniform diameter with the amount of material removed from said one of said surfaces on adjacent coils gradually increasing from a minimum at one end to a maximum at the opposite end, an input portion of said coaxial line connected to said one end of said

termination portion, and a member of microwave absorbing material disposed in peripheral proximity to said one of said surfaces of said termination portion.

5 6. Apparatus for absorbing incident power of electromagnetic waves within the microwave spectrum comprising a coaxial line having a center conductor surrounded by an outer tubular shield, a termination portion of said coaxial line coiled about an axis with axially adjacent coils defining radially inner and outer surfaces, said coaxial line of said termination portion decreasing in cross sectional area gradually from one end of said termination portion to an opposite end with said outer shield of said coaxial line of said termination portion having an opening facing radially from one of said surfaces with said opening progressively increasing from a minimum proximate said one end of said termination portion to a maximum at said opposite end, an input portion of said coaxial line at said one end of said termination portion, and a member of microwave absorbing material disposed in peripheral proximity to said one of said surfaces of said termination portion.

10 7. Apparatus for absorbing incident power of electromagnetic waves within the microwave spectrum comprising a generally tubular housing, a coaxial line disposed in said housing and having a center conductor surrounded by an outer tubular shield, a termination portion of said coaxial line coiled about an axis with axially adjacent coils defining radially inner and outer surfaces, said coaxial line of said termination portion decreasing in cross sectional area gradually from one end of said termination portion to an opposite end with said outer shield of said coaxial line of said termination portion having an opening facing radially from one of said surfaces with said opening progressively increasing from a minimum proximate said one end of said termination portion to a maximum at said opposite end, an input portion of said coaxial line at said one end of said termination portion having a terminus coextensive with one end of said housing and with said center conductor extending axially beyond said shield, connector means secured to said one end of said housing and operative with said terminus of said input portion to define an electrical connector, and a member of microwave absorbing material disposed in peripheral proximity to said one of said surfaces of said termination portion.

15 8. Apparatus for absorbing incident power of electromagnetic waves within the microwave spectrum comprising a coaxial line having a center conductor surrounded by an outer tubular shield, a termination portion of said coaxial line coiled about an axis with axially adjacent coils defining radially inner and outer surfaces, one of said surfaces of said termination portion tapered radially between one end and an opposite end, the other of said surfaces of said termination portion extending axially substantially radially uniformly with said outer shield of said coaxial line being partially removed to define an opening facing radially from said other of said surfaces and with said opening progressively increasing from a minimum proximate said one end to a maximum at said opposite end, an input portion of said coaxial line at said one end of said termination portion, and a member of microwave absorbing material disposed in peripheral proximity to said other of said surfaces of said termination portion.

20 9. Apparatus for absorbing incident power of electromagnetic waves within the microwave spectrum comprising a coaxial line having a center conductor surrounded by an outer tubular shield, a termination portion of said coaxial line coiled about an axis with axially adjacent coils defining radially inner and outer surfaces, one of said surfaces of said termination portion tapered radially between one end and an opposite end, the other of said surfaces of said termination portion extending axially substantially radially uniformly with said outer shield of said coaxial line being partially removed to define an opening

facing radially from said other of said surfaces and with said opening progressively increasing from a minimum proximate said one end to a maximum at said opposite end, said opening extending for a length at least equal to twice the wave length of the lowest microwave frequency to be absorbed, an input portion of said coaxial line at said one end of said termination portion, and a member of microwave absorbing material disposed in peripheral proximity to said other of said surfaces of said termination portion.

10. Apparatus for absorbing incident power of electromagnetic waves within the microwave spectrum comprising a coaxial line having a center conductor surrounded by an outer tubular shield, a termination portion of said coaxial line coiled about an axis with axially adjacent coils defining radially inner and outer surfaces, one of said surfaces of said termination portion tapered radially between one end and an opposite end, the other of said surfaces of said termination portion extending axially substantially radially uniformly, said coaxial line of said termination portion decreasing in cross-sectional area gradually from one end of said termination portion to approximately one-half its original cross sectional area at an opposite end with said outer shield of said coaxial line being partially removed to define an opening facing radially from said other surface and with said opening progressively increasing from a minimum proximate said one end to a maximum at said opposite end, an input portion of said coaxial line at said one end of said termination portion, and a member of microwave absorbing material disposed in peripheral proximity to said other of said surfaces of said termination portion.

11. Apparatus for absorbing incident power of electromagnetic waves within the microwave spectrum comprising a coaxial line having a center conductor surrounded by an outer tubular shield, a termination portion of said coaxial line coiled about an axis with axially adjacent coils defining radially inner and outer surfaces, said outer surface of said termination portion tapered radially inwardly from one end toward an opposite end, said inner surface of said termination portion extending axially substantially radially uniformly with said outer shield of said coaxial line being partially removed to define an opening facing radially inwardly and with said opening progressively increasing from a minimum proximate said one end to a maximum at said opposite end, an input portion of said coaxial line at said one end of said termination portion, and a member of microwave absorbing material disposed in peripheral proximity to said inner surface of said termination portion.

12. Apparatus for absorbing incident power of electromagnetic waves within the microwave spectrum comprising a coaxial line having a center conductor surrounded by an outer tubular shield, a termination portion of said coaxial line coiled about an axis with axially adjacent coils defining radially inner and outer surfaces, said inner surface of said termination portion tapered radially inwardly from one end toward an opposite end, said outer surface of said termination portion extending axially substantially radially uniformly with said outer shield of said coaxial line being partially removed to define an opening facing radially outwardly and with said opening

progressively increasing from a minimum proximate said opposite end to a maximum at said one end, an input portion of said coaxial line at said opposite end of said termination portion, and a member of microwave absorbing material disposed in peripheral proximity to said outer surface of said termination portion.

13. Apparatus for absorbing incident power of electromagnetic waves within the microwave spectrum comprising a generally tubular housing, a coaxial line disposed in said housing and having a center conductor surrounded by an outer tubular shield, a termination portion of said coaxial line coiled about an axis with axially adjacent coils defining radially inner and outer surfaces, said outer surface of said termination portion tapered radially inwardly from one end toward an opposite end, said inner surface of said termination portion extending axially substantially radially uniformly with said outer shield of said coaxial line being partially removed to define an opening facing radially inwardly and with said opening progressively increasing from a minimum proximate said one end to a maximum at said opposite end, an input portion of said coaxial line at said one end of said termination portion, a member of microwave absorbing material disposed in peripheral proximity to said inner surface of said termination portion, and means operatively associated with said member, said housing and said coaxial line for moving said member axially relative to said termination portion.

14. Apparatus for absorbing incident power of electromagnetic waves within the microwave spectrum comprising a generally tubular housing, a coaxial line disposed in said housing and having a center conductor surrounded by an outer tubular shield, a termination portion of said coaxial line coiled about an axis with axially adjacent coils defining radially inner and outer surfaces, said inner surface of said termination portion tapered radially inwardly from one end toward an opposite end, said other surface of said termination portion extending axially substantially radially uniformly with said outer shield of said coaxial line being partially removed to define an opening facing radially outwardly and with said opening progressively increasing from a minimum proximate said opposite end to a maximum at said one end, an input portion of said coaxial line at said opposite end of said termination portion, a member of microwave absorbing material disposed in peripheral proximity to said outer surface of said termination portion, and means operatively associated with said member, said housing, and said coaxial line for moving said member axially relative to said termination portion.
